UNITED STATES PATENT OFFICE

101,906

DESIGN FOR AN ARTIFICIAL BAIT

Harry R. Weaver, Wilkes-Barre, Pa.

Application September 17, 1935, Serial No. 58,602

Term of patent 14 years

To all whom it may concern:

Be it known that I, Harry R. Weaver, a citizen of the United States, residing at Wilkes-Barre, in the county of Luzerne and State of Pennsylvania, have invented a new, original, and ornamental Design for an Artificial Bait, of which the following is a specification, reference being had to the accompanying drawing, forming part thereof.

Figure 1 is a side elevation of an artificial bait showing my new design.

Figure 2 is a top plan view thereof.

Figure 3 is a bottom plan view thereof.

Figure 4 is a front elevation.

I claim:

The ornamental design for an artificial bait as shown.

HARRY R. WEAVER.
